UNITED STATES PATENT OFFICE.

ANDREW J. DUNCAN, OF YOUNGSTOWN, OHIO.

DESIGN FOR A CASING FOR OIL-CANS.

SPECIFICATION forming part of Design No. 20,639, dated March 24, 1891.

Application filed October 9, 1890. Serial No. 367,596. Term of patent 7 years.

To all whom it may concern:

Be it known that I, ANDREW J. DUNCAN, a citizen of the United States, and a resident of Youngstown, county of Mahoning, State of Ohio, have invented a new Design for Oil-Can Casings, of which the following is a full, clear, and exact description, reference being had to the accompanying drawings, making part of this specification.

10 My invention relates to a new design for an oil-can casing.

In the accompanying drawings, Figure 1 is a side elevation showing the can protected by the casing, and Fig. 2 is a top plan view.

15 The design consists of the top ring C to conform to the curved or oval top of the can

and ornamented by ribs or grooves c. This top ring is projected outward, as at G, to which are secured equidistant apart wire rods E, which, with their lower ends, are secured 20 to the flange c' of the supporting-ring C'. These rods secure the rings to the can, which, being of glass, is protected against breakage.

I claim—

The design for oil-can casings herein shown 25 and described.

In testimony whereof I have hereunto set my hand this 25th day of September, A. D. 1890.

ANDREW J. DUNCAN.
